UNITED STATES PATENT OFFICE.

ADELBERT A. DISBROW, OF STEVENSON, WASHINGTON.

WRITER'S AIDING DEVICE.

1,353,730.

Specification of Letters Patent. Patented Sept. 21, 1920.

Application filed September 8, 1919. Serial No. 322,337.

To all whom it may concern:

Be it known that I, ADELBERT A. DISBROW, a citizen of the United States, residing at Stevenson, in the county of Skamania, 5 and State of Washington, have invented certain new and useful Improvements in Writers' Aiding Devices; and I do declare the following to be a full, clear, and exact description of the invention, such as will enable others skilled in the art to which it 10 pertains to make and use the same.

This invention relates to writers' aiding devices, and more specifically to an improved pen and pencil attachment or holder 15 for correctly positioning the hand of a writer relative to the pen or pencil and relative to the surface being written upon.

One object of this invention is to provide an improved pen-embracing element which 20 is mounted for adjustment along the hand-supporting bar which constitutes an element of the invention, so as to accommodate hands of different sizes and shapes.

A further object is to provide an improved 25 pen or pencil holding device of this character in which the pen or pencil may be adjusted longitudinally while friction resistance is exerted in opposition to such adjustment.

30 Other objects and advantages may become apparent to persons who read the following details and description in connection with the accompanying drawings, in which:

Figure 1 is an elevation illustrating a 35 writer's hand supporting and being supported by a device constructed in accordance with the present invention.

Fig. 2 is a side elevation of one of my 40 improved writers' aiding devices.

Fig. 3 is a cross sectional view, the section being taken substantially along the line 3-3 of Fig. 2.

Fig. 4 is a view somewhat similar to Fig. 3, but showing a fragment of a writing instrument held by the spring wire-holding member.

Fig. 5 is a side elevation of the spring or holding member detached from the hand supporting bar.

50 Referring to these drawings in detail in which similar reference characters correspond with similar parts throughout the several views, the device comprises a hand-supporting bar 6 and a spring clamping or gripping member 7, the latter being preferably formed of a single length of springy

wire having its middle portion formed into a series of helical loops 8, its end portions being formed into curved gripping jaws 9. The gripping jaws 9 overlap one another 60 at points radially outward from the central portion of the series of loops 8, these jaws 9 being substantially parallel to one another and being open adjacent the ends of the series of loops 8. Therefore, when the 65 helical coil or series of loops 8 is compressed along its axis, the spaces between the gripping surfaces of the jaws 9 is widened and the bar 6 may be forced between these jaws, it being understood that the jaws may expand or slightly increase their radius in order to receive the larger end portion of the bar 6. However, when the jaws 9 are thus engaged with the bar 6, their spring action combined with that of the loops 8 70 cause the jaws 9 to frictionally hold the bar 6 so that it may be adjusted along the bar while resisting such adjustment. When thus applied to the bar, the loops 7 and their respective axes are arranged in a curve 75 so that when a pen, pencil or other writing instrument having a straight handle is passed through the series of loops, as illustrated in Fig. 4, the series is straightened thereby, but the tendency to assume the 80 curved position shown in Fig. 3 causes the coils to frictionally hold the writing instrument, so as to permit longitudinal adjustment.

The bar 6 is preferably formed with a 90 knob 10 which is supported by the surface on or adjacent to that which is to be written upon, and the little finger of the writer's hand embraces the bar 6 at the junction of the knob 10, so that the hand practically 95 rests upon or is supported by the knob 10, while the remaining portion of the bar 6, properly positions the hand with respect to the writing instrument and with respect to the surface to be written upon, also properly 100 positioning the writing instrument with relation to the hand and with relation to the surface to be written upon.

From the foregoing description in connection with the drawings, it will be seen that 105 the pen or writing instrument is adjustable both longitudinally and laterally with respect to the hand of the writer, while the hand retains a substantially fixed position with relation to the surface being written 110 upon.

Although I have described this embodi-

ment of my invention very specifically, it is not intended to limit this invention to these exact details of construction and arrangement, but changes may be made within the 5 scope of the inventive idea as implied and claimed.

What I claim as my invention is:

1. In a writer's aiding device for connecting a writing instrument to a hand-supporting bar, a spring-clamping member formed of a single piece of material which has its ends bent and combined to form a spring-clamp, said piece having its intermediate portion bent to form another spring-clamp, one of said spring-clamps being effective to receive and clamp said bar while the other spring-clamp is effective to receive and clamp said writing instrument.
2. A writer's aiding device comprising a bar adapted to be held in a person's hand and to support the hand above the surface to be written on, and a clamping device formed of a length of wire and comprising

a series of helical loops, portions of said wire constituting curved jaws which embrace and clamp said bar, the relation of the said clamping jaws and bar being such that the axes of the respective loops are arranged in an arc, said loops being of a size to receive a writing instrument therethrough 30 and coöperate in frictionally holding the writing instrument.

3. In a device for frictionally holding a writing instrument, a member formed of a length of springy wire and having its middle portion forming a series of helical loops, the end portions of said wire member forming arcuate clamping jaws which are substantially parallel with one another and which overlap one another at a point radially outward from said series of loops, for the purposes specified.

In testimony whereof I have hereunto set my hand.

ADELBERT A. DISBROW.
